COMBINED HANDLE AND HANDLE BRACKET FOR KITCHEN UTENSILS

James L. Hvale, Chicago, Ill., assignor to Ekco Products
Company, Chicago, Ill., a corporation of Illinois

Application March 5, 1958, Serial No. 49,918

Term of patent 3½ years

(Cl. D44—29)

Fig. 1 is a top view of a combined handle and handle bracket for kitchen utensils showing my new design.

Fig. 2 is an end elevational view thereof.

Fig. 3 is a front view taken in the direction of the arrows 3—3 in Fig. 2.

Fig. 4 is a bottom view taken in the direction of the arrows 4—4 of Fig. 2.

I claim:

The ornamental design for a combined handle and handle bracket for kitchen utensils, as shown.
